JOHN STUART FLEMING, OF TORONTO, ONTARIO, CANADA, ASSIGNOR, BY MESNE ASSIGNMENTS, TO NIAGARA FOLD, INC., OF NIAGARA FALLS, NEW YORK, A CORPORATION OF NEW YORK

MANIFOLDING WRITING MACHINE

Application filed October 6, 1927. Serial No. 224,352.

This invention relates to improvements in manifolding machines, and more particularly with reference to some of its details, it relates to improvements in supporting devices for carbon sheets or similar transfer strips utilized in manifolding writing. 5

It is a general object of the invention to provide, in machines of the class mentioned, an improved supporting and shifting arrangement for the transfer sheets or strips, which is simple and inexpensive in construction and effective and satisfactory in use. 10

A further object of the invention is to provide an improved transfer sheet holder 15 for machines of the class mentioned, which is applicable to different types of manifolding machines such as typewriters, autographic registers, billing machines, and the like, and which, moreover, is readily applicable to such machines of existing construction, and to those which are already in service.

A further object is to provide an improved device for machines of the class mentioned whereby the transfer sheets may be quickly 25 and easily shifted from one transfer position to another relatively to the record strips or webs.

Still another object is to provide a simple arrangement whereby the transfer strips and 30 record strips may be relatively adjusted to a new transfer position by provision of an improved and simple device whereby one of the strips is restrained from movement while another is moved relatively thereto.

A further object is to provide, in machines 35 of the class mentioned, an improved arrangement whereby relief to frictional restraint or binding action of the record strips to relative adjusting movement of the transfer strips is automatically accomplished at the desired period, and whereby adjustment of the strips to new transfer position is accomplished by a simple operation.

Another object is to provide an improved 45 carbon sheet holder for machines of the class mentioned which is movable to and beyond the platen, or other device for holding the record strips in manifolding position, so as to relieve the carbon sheets and record strips 50 from frictional restraint to relative move-

ment therebetween, permitting easy longitudinal adjustment.

In some of its aspects, this invention relates to manifolding machines, of the types above mentioned, for simultaneously writing inscriptions upon a plurality of superposed webs or record strips arranged for traveling or feeding movement, as successive blank forms or recording areas are inscribed, the successive inscribed areas or leaves ordinarily being intended to be severed from the main body of the record strips. Transfer strips, such as carbon sheets interleaved with the record strips, are ordinarily employed for transferring the original inscription to the underlying record strips. It is an object of the invention to provide an improved and practical device whereby the transfer sheets of the manifolding apparatus may be shifted from areas of the record 70 strips which have been written upon into manifolding position with reference to successive writing areas of the record strips. 65

Other objects of the invention will be in part pointed out in connection with the following detailed description of an illustrative but preferred embodiment of the invention, and will be in part obvious in connection 75 therewith.

The invention accordingly comprises the 80 features of construction, combinations of elements, and arrangement of parts, which will be exemplified in the construction herein-after set forth and the scope of the application of which will be indicated in the claims. 85

For a more complete understanding of the nature and objects of the invention, reference is had to the following detailed description, and to the accompanying drawings, in which:— 90

Fig. 1 is a front elevation of a typewriter of the cylindrical platen type, embodying the invention.

Fig. 2 is a perspective view of a supply 95 of superposed traveler record strips with an assembled form of improved carbon or transfer sheet carrier.

Fig. 3 is a front elevation similar to Fig. 1 but showing the traveler record strips with 100

the assembled carbon sheets and carbon carrier in a different relative position.

Fig. 4 is a cross sectional view substantially on the line 4—4 of Fig. 1, shown diagrammatically so as to facilitate disclosure.

Fig. 5 is a detailed perspective of one of the checking or stop lugs for the transfer sheet carrier.

Fig. 6 is a plan of one form of transfer sheet carrier, parts being broken away and in section.

Fig. 7 is a transverse section of Fig. 6.

Fig. 8 is a detailed view of the transfer sheet carrier, and

Fig. 9 is a perspective view of a modified form of transfer sheet carrier unit.

Referring to the drawing for a detailed description of the illustrative embodiment of the invention a typewriting machine of the cylindrical platen type of a well known design is shown for the purpose of illustrating the application of the invention. While the invention is herein shown as applied to a standard form of typewriter, it is to be understood that it may be applied as well to other types of typewriting machines including those employing the flat platen or flat writing bed, and also to autographic writing machines such as autographic registers, and the like. In the machine as shown, the cylinder platen 10 is rotatably mounted and arranged for manual operation, in a well known manner, on a carriage indicated generally at 11 and being movable longitudinally with reference to the type bars or other printing elements 12 which are mounted to strike against the paper or record strips supported on the platen between the prongs of the combined ribbon carrier and type guide plate 13. The ink ribbon 14 may be carried in any suitable manner and held in correct operative position by means of the plate 13. Pressure plates or bars 15 curved to conform to the cylindrical platen may be utilized to support and press the paper in smooth condition against the platen surface.

These pressure plates 15 may be of any preferred or standard design, and additional paper pressing and guiding means such as known in the art may be utilized for guiding and holding the paper sheets or strips in correct operative position upon the platen. These pressing devices are capable of holding a plurality of superposed record strips with interleaved transfer or carbon sheets in position upon the platen whereby the record impressed upon the outer sheet by the type bars may be transferred to one or to a plurality of underlying record strips. The platen 10 may be manually rotated by means of a knob 16 to feed the record strips forwardly and backwardly in a familiar manner to effect line spacing.

The invention is best utilized in connection with continuous or traveler record strips S,

each preferably having a series of blank forms 17 or similar inscription areas arranged therealong and separated by transverse weakened lines or perforations 18 whereby the forwardly fed parts of the record strips may be readily severed. The record strips are preferably assembled in superposed overlapping relation clearly shown in Fig. 2, and they may be folded in the form of a zigzag supply pad S' which may be supported by means of a supporting plate or bracket 19 either carried in any suitable manner by the writing machine or else independently supported. The bracket 19 is preferably fitted with adjustable clips 20 secured to the plate by means of pins extending into transversely extending slots 20a so as to permit transverse adjustment to accommodate different sizes of supply pads. In the drawing five superposed record strips are shown thus arranged, but it will be understood that a larger number may be utilized as may be found desirable in billing machines and autographic registers.

For supporting the transfer sheets C in overlapping manifolding position between the adjacent record strips S, a transfer sheet carrier or block, indicated generally at 21, is provided. This carrier may assume different forms but is preferably of sheet material and flexible transversely of its length so as to conform to the contour of the cylindrical platen, or to other curved surfaces or paths such as may be encountered in different types of machines. The carrier 21 may be made of heavy brown or manila paper so as to be flexible in any direction, but of sufficient weight and strength to function as a support for the relatively lighter and more fragile carbon paper sheets attached to it, or it may be made of other light similar flexible material such as textile fabric or light fiber board. It may be and preferably is constructed so as to be more flexible transversely of its length than it is longitudinally thereof.

The carrier 21, however, will be of sufficient stiffness and strength longitudinally to support the transfer sheets in smooth and manifolding position between the record strips and also of sufficient strength and stiffness to enable it to function as a shifter to move the transfer sheets longitudinally of the record strips from one manifolding position to another.

The detail construction of a preferred embodiment of the carrier 21 is shown in Figs. 6, 7, and 8 wherein a piece of flexible material such as tough brown paper is bent or folded into V-shape, one branch of which is provided with a series of parallel longitudinally extending spaced slits 22 for receiving the record strips S therethrough, as clearly shown in Fig. 7. These slits provide intermediate bars or attaching strips 23 to which the sheets C are attached as by an adhesive.

The attaching ends of the transfer sheets C pass through the slits 22 from the outside and are attached by the adhesive to the inner surfaces of the attaching bars 23 as best shown in Fig. 7. The attaching ends of the sheet C are thus protected from injury or from injuring the record strips, and they are further protected by the other side 24 of the V-shaped carrier which thus functions as a protective flap for these attaching ends. The outer sheet C at the right in Fig. 7 may be attached to the outer surface of the flap 24 as shown, or it may extend through the adjacent slit and be attached to the inner surface of said flap. The protective flap 24 also strengthens and reinforces the transfer sheet carrier 21.

The carrier 21 is made of sufficient length so as to project at opposite ends thereof beyond the adjacent edges of the record strips S as shown in Fig. 2, thus forming projecting lugs or stops 25 lying beyond the edges of the assembled record strips and functioning as checking members to check advancement of the carrier and transfer sheets so as to aid in relatively shifting said sheets longitudinally of the record strips as more fully described below. The bending or folding of the carrier sheet provides a longitudinally extending reenforcing rib or angle 26 for the lugs 25 as well as for the carrier generally.

The opposite ends of the transfer sheet carrier 21 may be cut away at their rearward faces so as to form rearwardly facing curved or inclined surfaces 27 which function as clearance surfaces during reverse movement of the carrier past the platen. In other words, these surfaces function to clear the way as the carrier passes by the platen thus avoiding obstruction to movement of said carrier.

In the illustrative embodiment of the invention, a pair of checking or stop lugs 28 are adjustably carried by a supporting bar 29 on the machine. These lugs or checks are shown as hooked shape and are connected to the rod 29 by tensioned gripping jaws 30 enabling the checks to be slid longitudinally upon the supporting rod for adjustment to accommodate different widths of record strips. The checks may also be swung angularly upon the supporting rod so as to correctly position the hook shaped parts for co-operation with the projecting lugs 25 of the transfer sheet carrier 21. The checking lugs 29 may thus be positioned so as to lie adjacent to the edges of the record strips S as they pass around the platen and in position to engage with the carrier 21. It will therefore be noticed that the checking lugs 28 are caused to engage automatically with the cooperating lugs of the carrier 21 so as to check said carrier when it has been freed from the grip of the platen.

The assembled record strips and carbon sheets as shown in Fig. 2, being placed in the

machine as best shown in Figs. 1 and 4, with the carbon sheets and recording areas of the strips in juxtaposition to the platen, the type bars are operated to impart the desired inscription upon the outer record strip, the inscription being transferred to the underlying strips by the carbon sheets in a manner well known in the art. As straps are fed forwardly for line spacing, the transfer sheet carrier 21 is also moved forwardly being carried along with the record strips. It will be understood that the record strips and transfer sheets will be gripped and pressed against the platen by the pressing and guiding bars 15, thus exerting friction upon the transfer sheets and carrier 21 by the contacting faces of the record strips, whereby relative longitudinal movement between the strips and carrier is resisted thus to restrain the carbon sheets in correct transfer position. In referring to Fig. 4, it should be kept in mind that this figure is partially diagrammatic, the sheets and strips being shown as separated in order to facilitate disclosure; in actual practice, the strips and transfer sheets will, of course, be held in smoothly contacting relation with each other.

When the carbon carrier 21 in its forward movement reaches the platen 10, it is enabled, due to its thin flexible character, to pass with the record strips through the path around the cylindrical platen, and to pass beyond the gripping influence of said platen entirely to the delivery side of the latter. The carbon sheet positioner or carrier 21 is enabled to thus pass entirely to the delivery side of the platen and to be freed from the feeding grip thereof due to the fact that it is discontinuous at its rear end; that is, it terminates at a short distance to the rearward of the adjacent ends of the transfer sheets so as to be passable with the latter wholly past the platen to a position corresponding to that shown in Fig. 3. As the carrier emerges at the front or delivery side of the platen, the frictional grip upon the carrier and transfer sheets is thus released so as to permit free relative longitudinal movement between the strips and the carrier, and transfer sheets carried by the latter. At about this instant, in the cycle of operations, the laterally extending lugs 25 of the carrier 21 encounter the hooks of the stop lugs 28 thus checking further advancement of the carrier and transfer sheets. This position of the carrier 21 is shown in Fig. 3.

When the carrier and transfer sheets are thus restrained from further advancement, the record strips may be fed forwardly as shown in Fig. 3, to bring the next successive set of superposed blank forms 17 into manifolding relation with reference to the transfer sheets. For this purpose it will be observed that the feeding grip of the platen upon the record strips may continue whereby said record strips may be fed forwardly to

the desired extent. The inscribed sheets then lie wholly beyond the ends of the transfer sheets and may be conveniently severed along the transverse weakened lines 18, or a tearing edge 5 may be provided to facilitate this operation. When the inscribed sheets are severed or before they are severed the platen may be reversely rotated to bring the new set of blank forms with interleaved transfer 10 sheets into writing position against the platen. During this movement, the transfer sheets and carrier are frictionally engaged between the record strips whereby the strips, carrier and transfer sheets are moved back- 15 wardly as a unit around the platen 10.

It will be observed that the transfer sheet supporting member 21 (or the corresponding member 21a—Fig. 9) is preferably flexible throughout its extent, and that it forms, in 20 effect, an extension of the transfer sheet or sheets extending to such position as to cooperate with the checking lugs described. Each such checking extension in the embodiment shown is positioned laterally beyond the 25 adjacent edges of the carbon sheets so as to cooperate with the checking lugs. While it will be observed that the checking extension thus arranged is very convenient, it may be varied in precise form and differently arranged with reference to the carbon sheets 30 and yet perform the checking function in the same manner. Each of these laterally disposed checking extensions 25 also cooperates with the corresponding checking lug 28 35 in order to keep the carbon sheets in their correctly aligned position in manifolding relation with the record sheets or to bring the carbon sheets back into correct position in case they should become disaligned with the 40 record strips or out of longitudinal alignment therewith.

Where it is desired to use a lesser number of record strips, a modified transfer sheet carrier 21a may be employed as shown in Fig. 45 9, to carry a single carbon sheet C attached thereto. The carrier 21a as will be understood is constructed of flexible material as in the case above described, and may be provided with the inclined clearance surfaces 27a at the 50 ends functioning as above described.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

I claim:

1. In a manifolding machine in combination, means for supporting for traveling movement a plurality of superposed record strips, with at least one interleaved transfer sheet, a carrier for said transfer sheet freely carried by said record strips, and a checking lug cooperative with said carrier after it has passed beyond said supporting means for checking traveling movement of said transfer sheet during traveling movement of the record strips. 70 75

2. In a manifolding machine, in combination, means for supporting for traveling movement a plurality of superposed record strips with at least one interleaved transfer sheet, means for imparting pressure upon said strips causing them to frictionally engage said transfer sheet, a carrier for said transfer sheet movable with said record strips 80 85 wholly beyond said pressure means and means for checking advancement of said transfer sheet with the record strips after passage of said transfer sheet and carrier beyond said pressure means. 90

3. In a manifolding machine, in combination, means for supporting for traveling movement a plurality of superposed record strips with at least one interleaved transfer sheet, a carrier for said transfer sheet movable with said record strips to and beyond the below mentioned pressure means, said carrier being provided with a lug, pressure means for exerting pressure upon said record strips causing them to frictionally engage said transfer sheet and said carrier but to release both when they have passed beyond the pressure means, and a lug cooperative with the lug of said carrier so as to restrain traveling movement of said transfer sheet and carrier with the record strips when both said transfer sheet and said carrier have passed beyond said pressure means. 95 100 105

4. In a manifolding machine, in combination, means for exerting pressure upon a plurality of superposed record strips so as to cause them to frictionally engage a transfer sheet interleaved in transfer relation with said strips whereby the transfer sheet is caused to be fed with said record strips, a curved platen surface for supporting the strips for reception of an inscription, a transfer sheet positioner extending from said transfer sheet and being thin so as to be passable with the transfer sheet by said platen, said positioner being discontinuous at its rear near said transfer sheet whereby it may pass with said sheet entirely beyond said platen, and a stop cooperating beyond said platen with said positioner to check traveling movement of the transfer sheet when said sheet has passed with the positioner beyond said platen and the platen pressure thereon released. 110 115 120 125

5. In a manifolding machine, in combination, a platen having a cylindrical strip sup-

- porting surface for supporting, for manifold inscription, a plurality of superposed record strips, whereby the strips are movable past the platen, a carbon carrier interleaved with the record strips and freely carried independently of the platen by said record strips and movable therewith wholly past said platen, said carrier being transversely flexible so as to conform approximately to said cylindrical platen surface, lugs carried by said carrier, and restraining means cooperating with said lugs beyond said platen so as to restrain traveling movement of said carrier during traveling movement of said carrier and strips. 5
- 10 6. In a manifolding machine, in combination, feeding and supporting means for a plurality of superposed record strips, a transfer sheet carrier freely supported by said record strips in interleaved position therewith and adapted to pass with the record strips to and entirely beyond said feeding and supporting means, a checking device engaging said transfer sheet carrier to check it when it has passed beyond said feeding and supporting means, 20 and a support for supporting said checking device for adjusting movement toward and away from the strip path and also laterally of said path. 25
- 15 7. In a manifolding machine, in combination, feeding and supporting means for a plurality of superposed record strips with a transfer sheet freely supported by said record strips in interleaved manifolding relation therewith and adapted to pass with the record strips to and entirely beyond said feeding and supporting means to the delivery side of the latter, and a checking device positioned beyond said feeding and supporting means at the delivery side thereof and cooperating 30 with said transfer sheet when the latter has passed beyond said feeding and supporting means so as to check said transfer sheet. 40
- 20 8. In a manifolding machine, in combination, means for supporting for traveling movement a plurality of superposed record strips with at least one interleaved transfer sheet, strip gripping feeding means for gripping said record strips to feed them together with said transfer sheet until the latter passes 45 beyond the feed grip entirely to the delivery side thereof so as to be freed from restraint by the feeding means, said transfer sheet having a checking extension which is thin and flexible so as to be passable through and beyond the feeding grip to the delivery side thereof, and a checking device automatically cooperating with said checking extension after the latter has passed to the delivery side of said feeding means so as to check said extension together with its transfer sheet. 55
- 25 9. In a manifolding machine, in combination, means for supporting for traveling movement a plurality of superposed record strips with at least one interleaved transfer sheet, strip gripping feeding means gripping 60
- 30 said record strips to feed them together with said transfer sheet until the latter passes beyond the feed grip entirely to the delivery side thereof so as to be freed from restraint by the feeding means, said transfer sheet having a lateral checking extension which is thin and flexible so as to be passable through and beyond the feeding grip to the delivery side thereof, and a checking device positioned in the longitudinal path of said checking extension and laterally outside of the transfer sheet edge at the delivery side of said feeding means and automatically cooperating in checking relation with said checking extension when the latter passes to the delivery side of the feeding means so as to check further advance of the transfer sheet. 70
- 35 10. In a manifolding machine, in combination, means for supporting for traveling movement a plurality of superposed record strips with at least one interleaved transfer sheet, strip gripping feeding means for gripping said record strips to feed them together with said transfer sheet until the latter passes beyond the feed grip entirely to the delivery side thereof so as to be freed from restraint by the feeding means, said transfer sheet having a checking extension adapted to pass with the transfer sheet to the delivery side of the feeding means, and a checking device positioned at the delivery side of said feeding means and cooperating with said checking extension after it has passed to the delivery side of said feeding means so as to check the advancement of said transfer sheet during continuance of the feeding grip of said feeding means with continued feed of the record strips thereby. 80
- 40 11. In a manifolding machine, in combination, a rotary platen for supporting for manifolding inscription a plurality of superposed record strips, and having feeding cooperation with the latter whereby the strips may be fed past the platen, a transfer sheet positioner connected to a transfer sheet for positioning the latter in transfer relation with said record strips, said positioner being flexible substantially throughout its extent and being discontinuous at its rear end at a short distance to the rear of the adjacent end of the transfer sheet so as to pass with said sheet by and entirely to the delivery side of the platen, and a checking member detached and separate from said transfer sheet positioner cooperating with said positioner when the latter has passed with its transfer sheet entirely to the delivery side of said platen so as to check and position the transfer sheet. 90
- 45 12. In a manifolding machine, in combination, a record strip gripping platen, a transfer sheet positioner connected to a transfer sheet positioned in interleaved transfer relation with record strips used in the machine whereby said transfer sheet and positioner are supported by said record strips to move 100
- 50 13. In a manifolding machine, in combination, a transfer sheet positioner connected to a transfer sheet positioned in interleaved transfer relation with record strips used in the machine whereby said transfer sheet and positioner are supported by said record strips to move 110
- 55 14. In a manifolding machine, in combination, a transfer sheet positioner connected to a transfer sheet positioned in interleaved transfer relation with record strips used in the machine whereby said transfer sheet and positioner are supported by said record strips to move 115
- 60 15. In a manifolding machine, in combination, a transfer sheet positioner connected to a transfer sheet positioned in interleaved transfer relation with record strips used in the machine whereby said transfer sheet and positioner are supported by said record strips to move 120
- 65 16. In a manifolding machine, in combination, a transfer sheet positioner connected to a transfer sheet positioned in interleaved transfer relation with record strips used in the machine whereby said transfer sheet and positioner are supported by said record strips to move 125

therewith, said positioner being discontinuous at its rear end at a short distance to the rear of the adjacent end of the transfer sheet and being thin and flexible substantially throughout its extent whereby it may pass with the transfer sheet by and wholly beyond the grip of said platen to the delivery side thereof, and a checking device positioned in the longitudinal path of said positioner at the delivery side of said platen and automatically engaging with said positioner at the delivery side of the platen so as to check the positioner with its transfer sheet after they have passed to the delivery side of the platen.

13. In a manifolding machine, in combination, a transfer sheet carrier positioned between superposed traveler record strips, feeding means for exerting feeding pressure upon said record strips so as to cause them to frictionally engage with said carrier and with a transfer sheet attached to said carrier and interleaved in transfer relation with said record strips, whereby said transfer sheet and carrier are caused to be fed with said record strips, said transfer sheet carrier being discontinuous at a short distance to the rear of its attachment with the transfer sheet whereby it may pass entirely beyond said feeding means to the delivery side of the latter while the feeding grip upon the record strips continues, and a checking device positioned beyond said feeding means and automatically engaging with said carrier when the latter has passed with the transfer sheet wholly to the delivery side of said feeding means so as to check said transfer sheet during continued feeding actuation of the record strips by said feeding means.

In testimony whereof I affix my signature.
JOHN STUART FLEMING.
